UNITED STATES PATENT OFFICE.

JAMES R. WALSH, OF JACKSONVILLE, FLORIDA, ASSIGNOR OF ONE-HALF
TO RHODERICK G. ROSS, OF JACKSONVILLE, FLORIDA.

BOWLING-ALLEY.

SPECIFICATION forming part of Letters Patent No. 752,133, dated February 16, 1904.

Application filed July 14, 1903. Serial No. 165,421. (No model.)

To all whom it may concern:

Be it known that I, JAMES R. WALSH, a citizen of the United States, residing at Jacksonville, in the county of Duval and State of Florida, have invented certain new and useful Improvements in Bowling-Alleys, of which the following is a specification.

This invention relates to a portable bowling-alley which is so constructed that the balls which have been bowled will all return from the pit to the head of the alley and all of the pins which have been knocked over may be simultaneously set up in position by the player at the head of the alley or by an attendant at the pit.

The object of the invention is to provide an alley of this nature which is simple to build, easy to handle, and convenient to use.

In the alley which is illustrated as embodying the invention strong cords attached to the pins lead through openings in the alley-floor at the respective pin-spots to sheaves secured to a shaft that may be rotated from the head of the alley or from the pit for drawing the pin-cords taut and causing the pins which have been knocked over to erect themselves in their respective places.

Figure 1 of the drawings is a side elevation of the alley with part broken away. Fig. 2 is a plan of the same. Fig. 3 is a view, on larger scale, of the under side of the pit end of the alley. Fig. 4 is a longitudinal vertical section of the pit end of the alley, showing the pin-cords drawn taut for erecting the pins. Fig. 5 is a longitudinal section, on slightly larger scale, illustrating the conditions of the cords of a pin erected and a pin that has been bowled into the pit; and Figs. 6 and 7 are detail views of a button that may be used for facilitating the attachment of the pin-cords.

The alley may be built of strips of wood in sections to facilitate transportation and covered with cloth to reduce noise when in use. Each side of the bowling-floor 1 is a gutter 2, outside of which is a side wall 3 to prevent balls from leaving the alley. The gutters may incline toward the pit 4, so that the balls which leave the floor will roll into the pit. A chute 5 inclines from beneath the floor of the

pit to a box 6 at the head of the alley, and the floor of the pit inclines to an opening over the chute, so that all balls bowled into the pit will return to the head of the alley. The floor of the pit is preferably hinged at one end, so that it may be lifted to facilitate access to the pin-erecting mechanism that is beneath.

A shaft 7 is supported transversely of the alley beneath the floor of the pit. At one side of the alley this shaft bears a sheave 8, wound about which is a cord 9, that leads to a handle 10 at the head of the alley. At the other side of the alley this shaft bears a crank 11 with a pair of crank-pins 12. By pulling the cord or by turning the crank-pins the shaft may be rotated. A spring 13 is connected with the shaft and with the shaft-support, so as to return the shaft to its normal position after it has been rotated by pulling the cord or turning the crank. Attached to the shaft are a number of sheaves 14 of different diameters, wound about which are cords 15, that lead through perforations in the floor of the alley and are attached to the lower ends of the pins 16. These cords may be made of rawhide, catgut, or any other suitable material and may be attached in any suitable manner to the respective pins, which are preferably made in the ordinary shape of wood. The cords are preferably separated and provided with loops and buttons 17, so that the parts may be disconnected when desired and the length of the cords adjusted when necessary. Sheaves 18 are provided to relieve the cords of friction, and the upper ends of the perforations through the floor are provided with eyelets 19, of hard wood, metal, or glass, to reduce the wear on the cords. The upper surfaces of the eyelets are preferably slightly recessed, and the lower ends of the pins are somewhat beveled, so as to insure their standing erect upon the eyelets. The perforations are made through the floor of the alley at the proper pin-spots, and the cords have sufficient slack to permit the pins to be knocked from their positions into the pit. The various pin-cord sheaves are so proportioned that the cords of the pins, which stand at different distances from the pit, will all be drawn taut simultaneously.

ously when the shaft with the sheaves are rotated by the hand-cord pulled by the player at the head of the alley or by the crank turned by the foot of the attendant at the pit. It is 5 preferred to connect the cord-sheaves with the shaft by means of a spiral spring 20, so that the sheaves will give when the pins are knocked over and the cords thus relieved of any sudden jerks.

10 The sides and end 21 at the pit end of the alley are preferably raised, so as to prevent the balls from bounding off from the alley, and these may, if desired, be padded to reduce the noise.

15 The pins, whether one or all are bowled over onto the floor or into the pit, may be instantly erected by pulling the cord at the head of the alley or by turning the crank at the pit with the foot. None of the balls can bound 20 off from the alley, and all, whether they roll in the gutter or continue on the floor into the pit, return to the player at the head of the alley.

The mechanisms described are simple to 25 construct and all of the parts are yielding, so that there will be no breakage on account of the varying lengths of the pin-cords and the shock given to the pins when they are hit by the balls and by each other.

30 I claim as my invention—

1. A bowling-alley having movable pins, sheaves of different diameters, cords of different lengths connecting the sheaves and the pins the longer cords being attached to the 35 larger sheaves, and means terminating at the head of the alley for rotating the sheaves and winding up the cords, substantially as specified.

2. A bowling-alley having movable pins, 40 sheaves of different diameters, a shaft supporting the sheaves, a spring connection between the sheaves and the shaft, flexible cords

of different lengths connecting the sheaves and the pins the longer cords being attached to the larger sheaves, and means terminating 45 at the head of the alley for rotating the shaft and winding up the cords, substantially as specified.

3. A bowling-alley having movable pins, sheaves of different diameters, cords of different lengths connecting the sheaves and the pins the longer cords being attached to the larger sheaves, loops and buttons connecting sections of the cords, and means terminating at the head of the alley for rotating the 55 sheaves and winding up the cords, substantially as specified.

4. A bowling-alley having perforations through the bowling-floor at the pin-spots, movable pins, sheaves of different diameter, 60 cords of different lengths leading from the pins through the perforations to the sheaves, the longer cords being attached to the larger sheaves, mechanism for rotating the sheaves and drawing the cords taut and means terminating at the head of the alley for operating the sheave mechanism, substantially as specified. 65

5. A bowling-alley having movable pins, a shaft extending transversely at the pit end of 70 the alley, sheaves of different diameters connected with the shaft, flexible cords of different lengths connected with the sheaves and leading through the perforations in the alley to the pins the longer cords being attached 75 to the larger sheaves, means terminating at the head of the alley for rotating the shaft in one direction and winding up the cords, and a spring for rotating the shaft in the opposite direction, substantially as specified.

JAMES R. WALSH.
